UNITED STATES PATENT OFFICE.

SANFORD E. WEST, OF PAWTUCKET, RHODE ISLAND, ASSIGNOR OF ONE-HALF TO GEORGE P. TYLER, OF EAST GREENWICH, RHODE ISLAND.

TOBACCO-PIPE.

No. 877,536.

Specification of Letters Patent.

Patented Jan. 28, 1908.

Application filed May 10, 1907. Serial No. 373,012.

To all whom it may concern:

Be it known that I, SANFORD E. WEST, a citizen of the United States, residing at the city of Pawtucket, in the county of Providence, State of Rhode Island, have invented 5 a certain new and useful Improvement in Tobacco-Pipes, of which the following is a specification.

My invention relates to an attachment 10 adapted to be secured within the bowl of a tobacco-pipe; and the object being to provide means to prevent liquid moisture from the tobacco accumulating in the bottom of the bowl, and thereby to obtain a dry smoke 15 from the pipe contents.

In the accompanying sheet of drawings, Figure 1 represents a perspective view of my improved attachment for a tobacco-pipe. Fig. 2 is a side view of a pipe with its bowl in 20 section, and illustrating a central vertical sectional view of the attachment applied to the pipe, as in use, Fig. 3 is a top plan section, taken on line $x-x$ of Fig. 2, and, Fig. 4 is a vertical section, taken on line $y-y$ of the 25 same.

Like reference characters indicate like parts.

My pipe attachment comprises two narrow metallic members a and b which are slidably mounted on each other.

The member a has a straight body portion a^1 which terminates with an upwardly curved extension a^2 , and the side portions of this member is bent and overlapping each 35 other to form outer projecting flanges a^3 , a^4 , to bear against the interior surface of the pipe-bowl c .

The member b has a straight body portion b^1 whose side edges are bent to overlap upon 40 and hold by frictional contact upon the overlapping edges a^4 of the body portion of the member a , and the upper part of this member b is bent laterally to form a tongue b^2 , which acts as a handle to remove the attachment 45 from the pipe.

When the attachment is placed within the pipe-bowl c the elasticity of the curved extension of the member a causes the flanges a^3 to bear outwardly in firm contact upon the 50 interior surface of the bottom of the bowl, thereby forming a sealed air draft orifice d which communicates directly with the air orifice d^1 , formed by the holding edges of the members a and b , and the orifice e of the pipe-

stem c^1 , in the manner shown in Figs. 2 and 3. 55

When the tobacco t is ignited the suction, created by the user of the pipe, causes the tobacco smoke to pass through the orifices d and e , in the direction indicated by the arrows 1 and 2 in Fig. 2, and at the same time 60 cold air passes through the orifice d^1 , in the direction indicated by the arrow 3 and mingles with the hot air withdrawn from the stem of the pipe. As the curved extension of the metallic member a becomes heated by 65 the burning tobacco, its radiation of heat is thrown off and tends to keep the bottom of the bowl c perfectly dry and free of liquid moisture, and at the same time the neutralization of the cold air with the hot air, 70 through their respective orifices, causes a regular even draft to be obtained through the stem of the pipe by the smoker. It is therefore evident that by my construction and arrangement of parts, I provide a device 75 that contains in itself all that is necessary to prevent liquid moisture from settling at the bottom of the pipe-bowl and clogging the orifice of the stem thereof, and at the same time a device that is simple, durable, is easily 80 applied to a pipe, and inexpensive to manufacture.

Having described my invention what I claim and desire to secure by Letters-Patent, 85

1. In a tobacco-pipe, an attachment adapted to be secured within the pipe-bowl and having a curved extension to fit the bottom of the latter and said attachment provided respectively with a cold air and a hot air passage to communicate with the orifice in the stem of the pipe. 90

2. The herein described attachment, comprising two metallic members, one of which has a straight body portion that terminates with an upwardly curved extension and said member having its side portions bent to form rear projecting flanges, and the other member having a straight body portion whose side edges are bent to hold by frictional contact upon the body portion of first mentioned member, and said second member terminating with a lateral rear extending tongue located above the body portion of first mentioned member. 100

3. In combination with a tobacco-pipe, of a device comprising two members, one of which members has an upwardly bent exten- 105

sion provided with outer projecting flanges so as to form a hot air passage entering the pipe-bowl and communicating with the orifice of the pipe-stem, and the other member 5 slidably mounted on first mentioned member and constructed so as to provide a cold air passage from the top of the pipe-bowl and communicating with the hot air passage of

first mentioned member, substantially as shown and for the purpose specified. 10

In testimony whereof I affix my signature in presence of two witnesses.

SANFORD E. WEST.
